CLAIM

The ornamental design for an electric guitar, as shown and described.

DESCRIPTION

FIG. 1 is a front elevational view of an electric guitar showing my new design;

FIG. 2 is a left side elevational view thereof;

FIG. 3 is a right side elevational view thereof; and

FIG. 4 is a rear elevational view thereof.

The broken lines of the guitar strings and electrical components in FIGS. 1, 2 and 3 are for illustrative purposes only and form no part of the claimed design.
